US00D978146S

(12) **United States Design Patent** (10) **Patent No.:** **US D978,146 S**
Haller et al. (45) **Date of Patent:** **** Feb. 14, 2023**

(54) **ELECTRONIC DEVICE**

(71) Applicant: **Elo Touch Solutions, Inc.**, Milpitas, CA (US)

(72) Inventors: **Jeffrey Haller**, Redwood City, CA (US); **Lukas Martin Scherrer**, San Francisco, CA (US)

(73) Assignee: **Elo Touch Solutions, Inc.**, Milpitas, CA (US)

(**) Term: **15 Years**

(21) Appl. No.: **29/808,506**

(22) Filed: **Sep. 20, 2021**

Related U.S. Application Data

(63) Continuation of application No. 29/684,237, filed on Mar. 19, 2019, now Pat. No. Des. 935,459.

(51) **LOC (14) Cl.** **14-02**

(52) **U.S. Cl.**

USPC **D14/375**

(57) **CLAIM**

The ornamental design for an electronic device, as shown and described.

DESCRIPTION

FIG. 1 is a top front perspective view of an electronic device showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top rear perspective view thereof.

The broken lines in the figures show portions of the electronic device that form no part of the claimed design.

1 Claim, 8 Drawing Sheets
